UNITED STATES PATENT OFFICE.

HARRY H. LABADIE, BURTON B. BEERS, AND THEODORE A. KRUEGER, OF CHICAGO, ILLINOIS; SAID BEERS AND SAID KRUEGER ASSIGNEES TO KNICKERBOCKER CASE COMPANY, OF CHICAGO, ILLINOIS, A CORPORATION OF ILLINOIS.

BAG.

Application filed January 29, 1923. Serial No. 615,585.

To all whom it may concern:

Be it known that we, HARRY H. LABADIE, BURTON B. BEERS, and THEODORE A. KRUEGER, citizens of the United States, residing at Chicago, in the county of Cook and State of Illinois, have invented certain new and useful Improvements in Bags, of which the following is a specification.

Our invention relates to bags, and it is the principal object of our invention to arrange a bag of the Gladstone type or appearance for use as a sample case.

It is a further object of our invention to provide a new and improved form and arrangement of parts by which the required strength of construction is attained without unduly increasing the weight, by reason of which the bag can without undue wear be subjected to hard usage for a long period of time and with heavy loads packed therein, and by reason of which the bag can be produced at a low labor cost, while at the same time due consideration is given to the appearance of the bag, both in its closed carrying condition and in its opened display condition.

It is another object of our invention to improve devices of this type in sundry details, hereinafter pointed out. The preferred means by which we have accomplished our several objects are illustrated in the drawings and are hereinafter specifically described. That which we believe to be new and desire to cover by Letters Patent is set forth in the claims.

In the drawings:

Fig. 1 is an end view of our improved bag in opened display condition, partly broken away at one point and showing in dotted lines the outline of the bag in its closed condition.

Fig. 2 is a horizontal cross-section, taken on line 2—2 of Fig. 1, but on an enlarged scale, being broken away for convenience of illustration.

Fig. 3 is an enlarged horizontal sectional view of one end portion of the bag, as shown in Fig. 2, but with the bag in closed condition;

Fig. 4 is an enlarged detail view, being substantially a vertical section taken on line 4—4 of Fig. 2;

Fig. 5 is an enlarged detail view, being

substantially a vertical section taken on line 5—5 of Fig. 3; and

Fig. 6 is a perspective view of the frame of one of the outer casing sections.

Referring to the several figures of the drawings, in which corresponding parts are indicated by the same reference characters, it will be seen that the bag as a whole comprises an intermediate base section, as shown in Fig. 1, with casing sections secured on opposite sides of the base section, so as to be capable of being folded down into substantial alignment with the bottom face of the base section, without causing the base section to be lifted or otherwise disturbed from its normal position resting upon the floor or other support.

In the form of construction illustrated in the drawings the base comprises a bottom part 10 in the form of a board which forms the bottom wall of an inside casing 11 which is open at its upper end. As is shown in Fig. 1, in the construction shown, the inside casing 11 is provided with a system of trays comprising a large bottom tray 12 and a plurality of smaller trays 13, supported upon the tray 12 and held adjustably in position thereon by means of pivoted links 14. The bottom tray 12 is also preferably removably held within the inner casing 11 by means of releasable clamping devices 15 of any suitable type. The system of trays and the means for holding the trays releasably in position within the inner casing 11, are preferably of the type described and claimed in the application filed on June 29, 1922, as Serial No. 571,638, in the name of Labadie, Beers and Brand. We do not desire to claim in the present application any of the subject matter disclosed by the said prior application.

Each of the outer casing members or sections comprises a side portion 16 (see Fig. 2), with end portions 17 and a top portion 18 secured about three edges of the side portion. The side portion 16 of each of the outer casing sections is preferably hinged to the bottom part of the base by means of an extension of the side portion which is secured directly to the base, the material of the side portion serving as the hinge. This hinge is also preferably reinforced at each end of the base by means of corner pieces of leather 19. As

will be readily appreciated, by this construction the lower edges of the end portions 17 are left free except for the connection at one point with the side portions 16.

5 As is ordinary in this type of bag, one of the outer casing sections is made slightly larger than the other so that when the sections are folded upwardly into closing position the larger section at its edge surrounds 10 the smaller section. The two sections are also provided with latching means of any suitable type for securing the sections together in carrying position, and the larger section is provided with a suitable handle 20. 15 Each of the outer casing sections is reinforced by a light metal framework, as is shown in Fig. 6 comprising a bow 21 formed of angle material and a bow 22 formed of a plain metal strip, the bows being secured together at right angles with respect to each other. As is shown in said Fig. 6, the wall 20 of the casing comprises a sheet 23 of paper, or similar stiffening material, secured by means of rivets about the framework. As 25 is clearly indicated in Fig. 3, the sheet 23 is covered on its outer face by a sheet of leather 24, which is glued to the sheet 23 and about the angle parts 21. On the inner face, a lining 25 of cloth or other suitable material is glued in position. By the use of this method of forming the sections, a very neat effect is attained, and there is no necessity for stitching the leather about the edges of the sections, as has been ordinary practice heretofore.

For receiving the free lower edges of the end portions of the outer casing sections, we have provided clips 26 at the ends of the base, each of the clips comprising a head 40 portion and a shank portion substantially perpendicular with respect to the head portion, the shank portions of the clips being secured upon the lower face of the bottom part 10. As is best shown in Fig. 5, when the 45 outer casing sections are swung upwardly into closing position, the free lower edges of the end portions 17 are brought into position to embrace the ends of the bottom part 10, the heads of the clips 26 being in such spaced relation to the bottom part 10 that the clips hold the end portions 17 in snug engagement with the ends of the part 10, when the casing sections are swung upwardly into closing position. As is best shown in Fig. 2, the bottom part 10 is preferably notched at 27 so as 50 to receive the casing sections with both of them in snug engagement with the bottom board 10. By this construction, with the clip 26 holding the end portions of the casing sections in position with respect to the base, the structure as a whole is reinforced and strengthened.

60 While we prefer to employ the form of construction illustrated in the drawing, and 65 above described, it will be understood that

we do not desire to limit ourselves to the details of this construction except as the same are specifically claimed, since it is evident that changes might be made in the construction without departing from the spirit of our invention.

70 We claim:

1. In a bag, the combination of a bottom board, casing sections each comprising a side portion hingedly connected along 75 one side of the bottom board, and end and top portions secured about three edges of the side portion, the end portions of the casing sections being adapted to embrace the ends of the bottom board which 80 is notched to receive them one within the other, means for latching the casing sections together in closing position, and clips mounted on the board and extending outwardly from the ends thereof adapted 85 to hold the free lower edges of the end portions of the casing sections in snug engagement with the ends of the bottom board when the casing sections are swung upwardly into closing position. 90

2. In a bag, the combination of a flat base portion, casing sections each comprising a side portion hingedly connected along 95 one side of the base, and end and top portions secured about three edges of the side portion, and means for latching the casing sections together, each of said casing sections comprising a strengthening metal framework about the free edges of the top and end portions and the lower edge of the 100 side portion, and angular clips projecting from the base for engaging the reinforced lower edges of the end members when in closed position.

3. In a bag, the combination of a base, 105 casing sections hingedly connected to the base at opposite sides thereof, and means for latching the casing sections together, each of said casing sections comprising a side portion, end and top portions secured 110 about three edges of the side portion, and a metal bow member secured at the lower edges of the side and end portions, and angular clips projecting from the base for 115 engaging the reinforced lower edges of the end members when in closed position.

4. In a bag, the combination of a base, casing sections hingedly connected to the base at opposite sides thereof, and means for 120 latching the casing sections together, each of said casing sections comprising a side portion, end and top portions secured about three edges of the side portion, a metal bow member secured at the free edges of the end and top portions, and a second metal bow 125 member secured at the lower edges of the side and end portions and also secured to said first-named bow member.

5. In a bag, the combination of a base, casing sections hingedly connected to the 130

base at opposite sides thereof, and means for latching the casing sections together, each of said casing sections comprising a side portion, end and top portions secured about 5 three edges of the side portion, a metal bow member formed of angle iron and secured at the free edges of the end and top portions of the casing member, and a second bow member secured at right angles to the 10 first named bow member and also secured at the lower edges of the side and end portions of the casing member.

6. In a bag, the combination of a base,

casing sections hingedly connected to the base at opposite sides thereof, and means 15 for latching the casing sections together, each of said casing sections comprising a strengthening metal framework, a sheet of stiffening material riveted to said framework, and a sheet of leather glued to the 20 outer face of the stiffening material and also folded and glued about the members of the framework.

HARRY H. LABADIE.

BURTON B. BEERS.
